TREATMENT OF HYDROCARBON OILS

George Armistead, Jr., Port Arthur, Tex., assignor
to The Texas Company, New York, N. Y., a corporation of Delaware

Application November 21, 1929, Serial No. 408,704

3 Claims. (Cl. 196—96)

This invention relates to the production of distillate oils and has particular application in the production of such distillate oils as gasoline or motor fuel and the like.

5 In general, the invention contemplates a process in which distillate oils, such for example as cracked distillates obtained from cracking processes, are subjected to distillation and fractionation by bringing them in contact with the 10 heat of vapors obtained in distilling residue derived from the cracking process. Thus, for example, hydrocarbon oil may be subjected to cracking and a distillate, such as a gasoline or naphtha distillate, and tar or residue, obtained 15 from the products of cracking. The tar or residue may be subjected to vaporization by means of its contained heat at reduced pressure and the evolved vapors subjected to fractionation in a fractionating tower while distillate obtained from 20 the cracking process is introduced as a reflux into the tower to thus supply cooling to the tower and for vaporizing the distillate to the extent desired, a vapor fraction of desired end point comprising vaporized constituents of the cracked 25 distillate as well as any vapors of desired boiling point obtained in the distillation of the residue being taken off the tower and collected as a condensate.

Experiments have shown that in cracking hydrocarbon oils by distillation under superatmospheric pressure a greater yield of gasoline or other light distillate of given end point can be most economically obtained, so far as the cracking operation is concerned, by taking off from the 30 dephlegmator or fractionating tower, employed in fractionating the vapors from the cracking still, a distillate having a higher end point than that of the given end point gasoline desired. Thus for example, assuming that it is desired to 35 obtain a 400° F. end point gasoline, if a distillate of for example 450° F. to 500° F. be taken off the pressure fractionating tower a greater amount of 400° F. end point gasoline will be produced by the apparatus than would be the 40 case if distillate of 400° F. end point were taken off. The reason for this is that the higher end point distillate taken off as a vapor from the tower requires a higher temperature in the top 45 of the tower than in the case of the lower end point distillate; the higher temperature at the top of the tower requires a correspondingly higher temperature in the still or reaction chamber which increases the cracking rate in the still 50 and thus results in increased cracking and yield

of gasoline. If it is sought to obtain this increased yield without increasing the end point of the pressure distillate it is necessary to apply more cooling to the tower to hold the end point down which results in an increased quantity of heat being consumed in vaporizing the greater quantity of reflux supplied to the tower and consequently an increased production in the tower of reflux condensate to be returned to the cracking zone, thereby causing an increase in fuel consumption that makes it impossible to increase the yield in this way as economically as by increasing the end point of the pressure distillate. When taking off the higher end point distillate it is necessary, however, to redistill and fractionate this distillate in order to obtain the lower end point product desired and the cost of this operation has hitherto negated the advantage obtained in the cracking operation of obtaining the maximum yield of fractions of desired 20 boiling point.

According to my invention the production of maximum quantities of gasoline or other distillate desired may be obtained by taking off from the pressure fractionating tower a distillate having a higher end point than that desired for the final product and, by directing this distillate as a reflux into a tower employed in fractionating vapors evolved in the auto distillation of the pressure tar or residue, the distillate 25 may be vaporized to the extent desired to form a final product of the desired end point. In this way the maximum production of gasoline or light distillate of desired distillation range is made 30 possible.

One aspect of the invention is concerned with certain novel improvements in the treatment of hydrocarbon vapors to render the hydrocarbons chemically stable and this phase of the invention 35 contemplates a process in which cracked distillate is brought into contact with the heat of vapors evolved in the distillation of cracked residue to thereby vaporize the cracked distillate and the resultant vapors then subjected to purifying or stabilizing treatment, such as by contacting them with suitable catalytic material.

When it is sought to purify or stabilize the light products from a pressure cracking still by passing the vapors, before final condensation, 40 through a mass of fuller's earth or other similar adsorbent treating material not only may the control and regulation of the cracking still be made more difficult but the product appears to be not as satisfactory when treated in this way 45

as it is when the vapor fraction is first condensed and then subjected to the treatment with the adsorbent clay at a lower pressure. The latter method of operation, however, involves an increased cost due to the necessity of revaporizing the distillate. In accordance with my invention hydrocarbon oil is subjected to cracking and distillation to form a light distillate, such as gasoline or naphtha, which is collected as a condensate and a tar or residue which is withdrawn from the cracking zone. This tar or residue is subjected to distillation by means of its contained heat at a lower pressure than that obtaining in the cracking zone to thus vaporize out any gasoline or naphtha constituents that may be contained therein as well as to recover therefrom constituents that are adapted for recycling or re-treatment for further cracking. The light distillate derived from the cracking operation is brought into contact with vapors evolved in the distillation of the cracked residue to thus vaporize the distillate, and the resultant vapors including the vaporized cracked distillate and light constituents derived from the distillation of the residue are treated with a solid adsorbent catalytic material such as fuller's earth or the like.

I have found that in the vaporization of the residue by auto-distillation there is frequently sufficient heat to effect a vaporization of the total gasoline or naphtha distillate derived from the cracking system in which such cracked residue was produced. Thus the invention may be applied to a single cracking still or battery of cracking stills or it may be applied to any convenient number of cracking stills. In accordance with the invention tar or residue may be withdrawn from a plurality of cracking stills or batteries thereof into a common distilling or vaporizing chamber for distillation at reduced pressure by means of the contained heat in the residues and the gasoline or naphtha distillates or condensates obtained from these cracking stills or batteries may be brought into contact with vapors evolved in the auto-distillation of the residues to thus vaporize the distillates and the resultant vapor product, including constituents of desired boiling point that have been vaporized out of the cracked residues and the vaporized pressure distillates, are subjected to treatment with adsorbent catalytic material such as fuller's earth and the like to effect polymerization of unstable constituents.

In order to more fully disclose the invention reference will now be had to the accompanying drawing which illustrates schematically a preferred apparatus adapted for the practice of the invention.

In the apparatus thus illustrated a cracking system including a heating coil 10 mounted in a furnace 11 and a still or cracking chamber 12 adapted to receive the heated oil from the coil 10 is shown. The oil to be treated which may be gas oil, or residual oil, or any of the petroleum stocks suitable for cracking, is drawn from a suitable source by a pump 13 which operates to charge the oil through the coil 10 and thence after heating to the still 12. Any suitable temperature and pressure conditions adapted for cracking may be employed in either or both the coil 10 and still or reaction chamber 12.

The still 12 is shown in vapor communication with a dephlegmator or fractionating tower 14 adapted for separating out as a vapor the gasoline or light distillate desired, which is passed to

a condenser coil 15 for condensation, and a liquid fraction which collects in the bottom of the tower and may be removed by a pump 16 through line 17 and charged through line 18 to the coil 10. In the operation of the tower 14 cooling may be supplied to the tower in order to regulate the end point of the vapor fraction taken off to the condenser 15. The condensate obtained in the coil 15 is collected in a receiving drum 19 and this condensate constitutes the gasoline or light distillate that it may be desired to purify or stabilize.

Tar or residue formed in the still 12 is withdrawn through a line 20 which extends to a tar or residue header 21 to which may be connected other residue lines, such as 22 and 23, which may extend to other batteries of cracking stills (not shown). The residue thus discharged into the line 21 is passed through a pressure reducing valve 24 and thence into a tank 25 which preferably constitutes a surge drum or cushioning drum to absorb the shocks or differences in pressure that may occur due to the drawing of tar by shots from the different pressure batteries to which the line 21 may be connected and so as to thus deliver a more or less constant stream of residual oil through a line 26 to a distilling chamber 27. It is preferable to reduce so far as possible variations in pressure in the distilling chamber 27 in order that the end point of the distillate obtained from the stripping apparatus may be constantly kept maintained at the point desired and thus it is desirable to either draw tar or residue continuously from the pressure batteries or to provide some such cushioning device as the chamber 26. It may be pointed out that by having a considerable number of batteries, such for example as 10 or 15, connected up to a single residue stripping unit, that by properly timing the withdrawal of liquid from the several batteries the influx of material into the stripping apparatus may be kept at a fairly constant rate so as to insure fairly constant distilling conditions.

The vaporizing chamber 27 may be of any suitable form and is shown provided with a vapor line 28, a residue draw-off line 29 and a section of contact material 30 which may be adapted to prevent tarry or mist particles from passing into the vapor line. If desired steam may be introduced to aid vaporization in the still 27, although ordinarily the heat contained in the residue will be found ample. The still 27 may be operated at pressures approximating atmospheric, although moderate superatmospheric pressures of for example 25 or 50 pounds may be used to advantage. There appears to be no particular advantage in operating the still under a subatmospheric pressure.

The fractionating tower 31 is shown is provided with a partitioning wall 32 which divides the tower into an upper and lower section. The vapor line 28 is shown discharging into the lower part of the upper section and a plurality of bubble trays 33 or other suitable contact material are indicated for the fractionation of the vapors. The lower section of the tower constitutes a stripping section and a line 34 having valved branch lines 35 extending to certain of the trays in the upper section is adapted for withdrawing liquid from these trays and delivering it into the lower section of the tower. Trays 36 or other suitable contact material and means 37 for introducing steam are shown in the lower section of the tower. A vapor line 38 operates

to conduct vapors from the lower section of the tower to the upper section of the tower. A line 39 is provided for withdrawing condensate from the upper section of the tower 31 and a line 40 5 is provided for withdrawing condensate from the lower section of the tower. These condensates are suitable as cycle stocks for re-cracking.

A line 41 equipped with valved branch lines 42 is provided for introducing cracked distillate 10 to be vaporized in the tower 31. The line 41 is shown as extending to a pump 43 having an inlet line 44 extending to the receiving drum 19 and provided with branch lines 46 and 47 which extend to the receiving drums of other pressure 15 batteries or to other sources of unstable distillate (not shown). If desired, the various distillates from the several receiving drums may be conducted to a single storage tank and the pump 43 arranged to take suction on this tank.

20 The liquid that is introduced by the pump 43 to the fractionating tower 31 serves as a cooling reflux for the vapors and this liquid may be partially or wholly vaporized in the tower by reason of the contact with the hot vapors rising 25 through the tower. Thus if the distillate introduced from the line 41 is of the end point desired for the final product it may be substantially wholly vaporized in the tower, or if the distillate be of a higher end point it may be vaporized 30 in the tower to the extent desired to obtain an overhead vapor product of desired end point while the higher boiling constituents may descend through the tower to be removed as condensate therefrom. When introducing to the 35 tower 31 distillate from the line 41 having a higher end point than that desired for the overhead vapor fraction it is advantageous to introduce the distillate or reflux at an intermediate point in the tower wherein the end point of the 40 liquid on the tray may approximate that of such reflux, and when operating in this manner additional reflux, such for example as distillate from the receiving drum 58, or other liquid having approximately the same end point or composition 45 as that of the vapor fraction being taken off the top of the tower 31, may advantageously be introduced to the top tray of the tower. When the reflux introduced to the tower has the same end point as that of the desired vapor fraction 50 it may advantageously be admitted to the top tray.

In some cases it may be desirable to preheat the distillate employed as reflux before introducing it into the tower 31. Thus when the production 55 of naphtha from a given cracking unit or a given number of such units is of such proportion to the vapors evolved in stripping the residue from such cracking unit or units as not to allow the desired vaporization of the distillate by means 60 of these vapors it is of advantage to preheat the distillate before introducing it to the tower 31 thereby lessening the heat required for vaporization of a given quantity of distillate and permitting a greater amount of distillate to be used 65 as reflux for a given amount of vapor evolved in the residue stripping tower 27. By preheating the distillate to be used as reflux it is possible to utilize more distillate from extraneous sources which it may be desired to use as reflux. This 70 preheating may be used to advantage in cases, for example, where the end point of the distillate used as reflux is higher than that of the vapor fraction desired. By providing the line 41 with branch lines extending to a suitable heating 75 coil which may for example be positioned in the

tower 14 to effect heat exchange with vapors therein or may be arranged in heat exchange with the hot residue as withdrawn through line 29, a portion or all of the distillate used as reflux may be preheated before introduction into the 5 tower 31.

The vapors from the tower 31 which comprise the vaporized cracked distillate that has been introduced thereto as reflux together with constituents of desired boiling point distilled out 10 of the cracked residue may be passed directly to a condenser but in the apparatus shown in the drawing a vapor line 48 is indicated for directing the vapors into a treating chamber 49 which contains a bed of solid adsorbent catalytic 15 material 50, such as fuller's earth or clay adapted for effecting a polymerization of unsaturated or unstable constituents in the vapors. The resultant polymers or liquid product thus obtained collects in the bottom of the chamber 49 and 20 may be drawn off by a pump 51 through line 52 and discharged through a line 53 and branch lines 54 into the tower 31.

The vapors leave the tower 49 through a vapor 25 line 55 by which they are conducted to a scrubbing or fractionating tower 56 which may serve as a mist extractor, as well as a fractionating device more particularly in the earlier parts of the run when the end point of the vapors may run higher than that desired. The vapors pass to a condenser coil 57 wherein they are condensed and the condensate is collected in a receiving 30 drum 58. A pump 59 is shown having a line 60 taking suction on the receiving drum 58 and a discharge line 61 extending to the tower 56 so that whenever desired liquid from the receiver 58 may be employed as a reflux for this tower. A backtrap or reflux line 62 is shown for refluxing 35 to the bottom of the chamber 49 liquid collected in the lower part of the tower 56.

40 One method of operation contemplated by the invention is to maintain the residue stripping still 30 under a vacuum which may advantageously be accomplished by the use of a vacuum pump in connection with the receiving drum 58, 45 the pump being preferably arranged to take suction on a gas line extending from the receiving drum, and a pump may also be used in the line 29 for withdrawing residue from the still 27. In this method of operation the treating of the 50 vapors by the contact material 50 is carried on under a vacuum. In another method of operation the pressure tar or residue is distilled in a two stage operation by being first distilled at atmospheric pressure or at a relatively low superatmospheric pressure and the residue from this distilling operation conducted to a secondary still 55 which is maintained under a vacuum wherein the final distillation takes place. In this method of operation the lighter constituents will come off in the primary distillation and the fractionation of these vapors and the treatment of the light vapor fraction by the catalytic contact material may take place under the pressure at which the primary distilling operation is conducted.

60 The final product as obtained in the receiving drum 58 may be passed to a rectifying tower for rectification whenever necessary or desirable in order to produce a product of desired vapor tension or, if desired, the distillate collected in the line 44 may be subjected to rectification before 65 being introduced to the tower 31.

70 Although the preferred embodiment of the invention has been set forth in connection with apparatus having a particular construction and ar- 75

angement of parts and mode of operation, it is obvious that various changes and modifications may be made therein, while securing to a greater or less extent some or all of the benefits of the 5 invention, without departing from the spirit and scope thereof. Therefore, only such limitations should be imposed as are indicated in the appended claims.

I claim:

10 1. The process of treating hydrocarbon oil which comprises subjecting said oil to cracking temperature under superatmospheric pressure to cause conversion thereof into lighter products, separating the resulting hot cracked products into 15 a distillate of a given end point higher than that desired for the final product and a hot residue, vaporizing said residue by reducing the pressure thereon, redistilling said distillate by thermal contact with the vapors derived from the vaporized 20 residue, fractionating the combined vapors to separate vapors of the desired end point, and treating said vapors last mentioned, while still hot, with solid adsorbent catalytic material to effect polymerization of unstable constituents and

form a desired product free from said distillate first mentioned.

2. A process according to claim 1 wherein polymers condensed by treatment of the said vapors last mentioned are used as reflux in the 5 fractionating of said combined vapors.

3. The process of treating hydrocarbon oil which comprises subjecting said oil to cracking temperature under superatmospheric pressure to cause conversion thereof into lighter products, 10 separating the resulting hot cracked products into a distillate of a given end point and a hot residue, subjecting the residue to auto-distillation by reducing the pressure thereon, entirely redistilling said distillate by thermal contact with the vapors derived from the vaporized residue, to produce a distillate of lower end point, and treating the combined vapors, free from undistilled portions of said distillate first mentioned, under 15 said reduced pressure with a solid adsorbent catalytic material to effect polymerization of unstable constituents and form a final desired product free from said distillate first mentioned.
